UNITED STATES PATENT OFFICE.

GEORGE B. MAEGLY, OF KANSAS CITY, MISSOURI.

IGNITION-SPARK-CONTROLLING MECHANISM.

1,277,447.

Specification of Letters Patent. Patented Sept. 3, 1918.

Application filed July 12, 1915. Serial No. 39,454.

To all whom it may concern:

Be it known that I, GEORGE B. MAEGLY, a citizen of the United States, residing at Kansas City, in the county of Jackson and

5 State of Missouri, have invented certain new and useful Improvements in Ignition-Spark-Controlling Mechanism; and I do declare the following to be a full, clear, and exact description of the invention, such as will enable others skilled in the art to which it 10 pertains to make and use the same, reference being had to the accompanying drawings, and to the letters and figures of reference marked thereon, which form a part of this

15 specification.

My invention relates to ignition-spark controlling mechanism for hydrocarbon motors having throttle control, and has for its principal object to provide a mechanical device 20 that is operable by the throttle to advance and retard the spark simultaneously with the throttle movement, and which comprises a manual adjustment for predetermining the limit of spark advance or retard, and the 25 range of spark movement for any range of throttle movement.

As the efficiency of the motor depends very largely on the relationship of motor speed to the time in the cycle at which the spark occurs, it is therefore desirable to provide some 30 means whereby the adjustment of the spark can be controlled by the throttle. As both throttle and spark are governing factors, and as the relationship between the two 35 varies under different conditions, a positive connection would not answer as the motor requires more throttle opening with less advanced spark when working at lower speed under heavy load, and less throttle opening 40 and more advanced spark with lighter load and high speed.

My invention, therefore, is intended and primarily adapted for mechanically connecting the throttle and spark timing mechanism 45 in such a manner that opening the throttle will simultaneously advance the spark to a degree, determined by adjustment, but whereby further throttle opening may be had without further advancing the spark; 50 the adjusting mechanism being so constructed and assembled with the spark-timer and throttle, that any predetermined degree of advance or retard may be had for any range of throttle opening.

55 A further object is to provide a device that will automatically advance and retard

the spark to the limit allowed by the adjustment upon the first or initial throttle movement, and at the same time have such spark movement synchronize with that of the 60 throttle.

A further object is to provide a device with which, while being both mechanical and automatic with the throttle, it is possible to move the spark timing mechanism 65 independently of the throttle, and which will also permit the throttle to be actuated without moving the timing mechanism when it is desired to hold the latter in either fully advanced or retarded position.

A further object is to provide means adapted to hold either full advance or retard as may be desired, or to automatically give a limited range of spark movement for any 70 range of throttle opening or either a limited 75 or extended amount of spark advance when desired for a limited amount of throttle opening.

In accomplishing these objects I have provided a device for adjustably fixing the degree of advance or retard beyond which in 80 either case, the spark cannot be automatically carried.

The preferred form of the invention is 85 illustrated in the accompanying drawings, wherein:—

Figure I is an elevation of a spark-controlling mechanism comprising my improvements and illustrating its connection with an ignition device, a throttle valve, an adjusting 90 lever, and a foot accelerator, showing the parts with closed throttle and full retarded spark, and the adjusting mechanism in what I term neutral position, as it has no effect 95 on the ignition spark controlling mechanism to limit either spark advance or retard.

Fig. II is a similar view showing partly opened throttle and fully advanced spark with the adjustment stop in what I term full advance position as it there holds the 100 spark controlling mechanism in fully advanced position.

Fig. III is a similar view, showing the parts as they appear for fully opened throttle and fully retarded spark, with the 105 adjusting stop in what I term full retard position as it here holds the spark controlling mechanism in fully retarded position, so that there is no ignition.

Fig. IV is a similar view, showing the 110 adjusting stop in three-quarter retard, or in position for limiting spark advance to a

range of from full retard to within one-quarter of full advance.

Fig. V is a similar view, having the adjusting stop in three-quarter advance, or in position for limiting spark advance to a range of from three-quarter advance to full advance; the adjusting stop holding the spark controlling mechanism on closing movement of the throttle so that it cannot return to full retard but must start on three-quarter advance upon opening of the throttle.

Fig. VI is a cross section on the line VI—VI, Fig. IV.

15 Referring more in detail to the drawings:—

1 designates an ignition device having a lever 2 for governing the spark-timing mechanism, 3 the intake manifold, 4 the 20 throttle valve of a carburetor (not shown), having an actuating lever 5, 6 a foot pedal that is operably connected with the throttle lever, as will presently be described, and 7 a steering post, which parts may be of any 25 ordinary construction as they, in themselves, form no part of my present invention.

Mounted on any permanent base, preferably on the motor, (not shown) is a frame 9, preferably U-shaped, the arm 10 of which 30 is slightly longer than the arm 11, and slidably mounted in said arms is a rod 12; one end of which is pivotally connected with the throttle lever 5 by a link 13, which is pivoted to the lever and to the arm.

35 Pivots mounted on the opposite end of the rod is a link 14, the outer end of which is pivotally connected with a lever 15 that is mounted in a yoke 16, and carries the pedal 6, an expansion spring 17 surrounding 40 the rod between the frame arm 10, and a collar 18 on the rod, so that when the pedal is depressed against the tension of spring 17, the rod 12 is drawn backwardly and the throttle lever actuated to open the throttle 45 valve. The spring 17 normally retains the parts in position for closing the throttle and automatically returns the same to such position when pressure is removed from the pedal.

50 Slidably mounted on the rod 12, between the frame arms 10 and 11 is a yoke 19, the arms 20 and 21 of which are apertured to slide on the rod 12 and to allow the rod to slide therethrough. The body of the yoke 55 carries a boss 23, and fixed to the boss, and slidably mounted in the long arm 10 of the frame, is a rod 24, having a link 25 pivotally connected therewith and with the timing lever 2 to operatively connect the lever with the yoke; the timing lever being normally urged toward its fully retarding position by an expansion spring 26, which is mounted on the rod 24 and bears against the frame arm 10 and against a collar 27 on the rod, 60 so that the timing lever is normally, yield-

ingly tensioned toward retarded position, and is automatically returned to such position when released.

As the position of the yoke determines the timing of the spark, means must be provided 70 for holding the yoke in an adjusted position, when a definite range of spark advance or retard is desired; the means here shown consisting of a cramp arm 29, having an aperture 30 therein, through which the rod 75 12 is extended, and through which the rod may move freely when the arm is perpendicular to the rod. The arm is pivotally anchored to the yoke 19 however, to slide therethrough, and urged along the rod by 80 an expansion spring 32 that is connected with the frame arm 10 and with the cramp arm, so that under normal conditions the arm cramps on the rod and locks the yoke thereto so that when the throttle rod 12 is 85 shifted by the foot pedal the yoke is moved with the arm to advance the spark.

The tension of the spring is sufficient to overcome the resistance of the timing lever, so that when the rod 12 is returned by the 90 spring 17, the initial return movement of the rod moves the timing lever 2 to the limit of its retarding movement, and further movement of the rod straightens the cramp arm against the tension of its spring 95 to allow the rod to pass through the arm aperture without affecting the timing lever.

The preferred mounting of the cramp arm 29 includes a rod 34—35 that is mounted in and extends between the frame arms 10, 100 11; the sections of the rod being of different diameter and meeting in a shoulder 36 at about the center of the frame. The cramp arm 29 has a slot 37 in its upper end so that it may slide in the small section of the rod 105 and engage the shoulder to stop movement of the arm at that point; the lower end of the arm being pivotally mounted on the body of the yoke 19 to allow the arm to rock, as described.

With the parts combined in this manner, with the throttle closed, the cramp arm is spaced from the shoulder (Fig. I), and the timing lever is at full retard position.

When the throttle is opened by advancing 115 the rod 12, the arm 29, being cramped on the rod, moves therewith and advances the spark proportionately to the opening of the throttle, until the cramp arm engages the shoulder 36 and is straightened to permit 120 the rod 12 to move freely therethrough; the arrangement being such that when the cramp arm reaches the shoulder the timing lever will be in fully advanced position, so that further movement of the rod will permit 125 the same to slide through the cramp arm and continue to open the throttle without affecting the timing mechanism. On return movement of the rod 12, under tension of spring 17, the cramp arm locks to 130

the rod upon initial movement of the rod and retards the spark immediately upon the initial closing movement of the throttle, the closing movement of the cramp arm and 5 yoke 19 continuing until the end of the yoke contacts the frame arm 10, where the yoke is stopped, and further movement of the rod is independent of movement of the cramp arm and yoke.

10 It is apparent that this part of the mechanism merely provides for spark advance and retard proportionately to the throttle action between full advance and full retard, but affords no regulation for intermediate points 15 and cannot adjust the range of spark advance. In order, therefore, to provide such intermediate or range regulation I have provided means for releasing the cramp arm from the rod 12 to limit the spark advance 20 and for stopping the yoke 19 to limit the spark retard at intermediate points.

This mechanism consists of a stop arm 39 which is slidably mounted on a rod 40, fixedly mounted between the frame arms 10, 25 11, and slidably mounted on the rod 34—35 and the rod 14; the width of the arm being sufficient to form a stop for the arm 21 of yoke 19 and for the cramp arm 29.

Fixed to an extension 42 on the stop arm 30 39, by a set screw 43, is a wire 44 that is slidably mounted in a conduit 45 that is fixed to an extension 46 on the frame 9 by a set screw 47 and extends to a quadrant 48 on the steering post 7; the wire extending 35 from the upper end of the conduit and connecting with a lever 48 on the quadrant.

With this arrangement, should it be desired to hold the ignition lever at fully retarding position, so that there would be no 40 ignition advance when the throttle is opened, the hand lever 49 is moved to slide the stop arm 39 toward the left, past the shoulder 36 until it engages the cramp arm 29 (Fig. III) and strengthens the arm.

45 With the stop arm so positioned, when the rod 12 is advanced to open the throttle, the cramp arm 29 engages the stop arm 39 and releases the rod 12 so that the rod 12 may be drawn forwardly to open the throttle; 50 this movement having no effect on the ignition mechanism, as the rod slides freely through the cramp arm and does not induce movement of the yoke 19.

Should it be desired, however, to provide 55 a range of from full retard to any desired advance, say three-quarters advance, the stop arm is moved to the position shown in Fig. IV, where it will permit some movement of the cramp arm but wherein the 60 cramp arm will engage the stop arm and release the rod 12, earlier than the rod would have been released if the cramp arm had traveled on to contact with the shoulder 36, and so that the spark is not advanced to the 65 extent it would have been without the ad-

jusment of the stop arm. When the cramp arm is stopped in this position, the rod moves on as before and continues to open the throttle but without fully advancing the spark. On the return of the rod 12 to 70 close the throttle, the cramp arm takes hold of the rod immediately upon movement of the rod, so that the primary throttle closing movement of the rod retards the spark and final closing of the throttle is effected after 75 the spark has been fully retarded.

Should it be desired to start the motor with an advanced spark, say a three-quarter advance, and increase the advance proportionately to the opening of the throttle until 80 the spark is fully advanced, the stop arm is drawn to the right (Fig. V), and engages the yoke arm 21 to carry the yoke along with it and advance the timing lever 2 to the desired position, so that when the throttle rod 12 is drawn forwardly to open the throttle, the cramp arm locks thereon and carries the yoke 19 along with it until the spark is fully advanced. On release of the throttle rod, the rod returns automatically, 85 under tension of its spring to close the throttle, the cramp arm taking hold to retard the spark and moving the yoke 19 back until the arm 21 engages the stop arm 39 to hold the yoke and timing lever while the throttle 90 closes, so that when the throttle is again opened the spark will start at the advanced position and continue to advance as the throttle is opened until it reaches the fully advanced position. 100

Having thus described my invention, what I claim as new therein, and desire to secure by Letters-Patent, is:

1. The combination with control mechanisms for a spark timer and a throttle, of 105 means automatically operable by manipulation of the throttle control mechanism for establishing and breaking co-operative relation between the two mechanisms.

2. The combination with a spark timer 110 movable within defined limits, and throttle control mechanism having movement in excess of that of the spark timer, of means adapted for establishing and breaking co-operative relation between the said timer and 115 the throttle control mechanism.

3. The combination with throttle and spark controlling devices, of releasable connection between said devices, and means for effecting the release of said connection to 120 permit movement of one device independently of the other.

4. The combination with throttle and spark controlling devices, of releasable connection between said devices, and adjustable 125 means for effecting the release of said connection to permit movement of one device independently of the other within a range determined by position of said adjustable means. 130

5. The combination with throttle and spark controlling devices, of means normally, operatively connecting said devices, and means for actuating said connecting means to break the connection, the connecting means being arranged to effect its operative connection upon initial movement of either of said devices in either direction.

6. The combination with throttle and spark controlling devices, of a member mounted on one of the devices and adapted for gripping the other to effect coöperation of the devices, and means for actuating said member to break its grip on the second device to permit independent actuation of the latter.

7. The combination with throttle and ignition spark devices, of means for actuating the throttle, slip connection between the 20 throttle and the ignition spark and adapted for moving the latter upon initial movement of the former, in either direction, and means for breaking such connection at a given point to permit independent movement of 25 the throttle device.

8. The combination with throttle and ignition spark devices, of means for actuating the throttle, slip connection between the throttle and the ignition spark devices, 30 whereby the latter may be moved upon initial movement of the throttle device in either direction, means for breaking such connection at a given point to permit independent movement of the throttle device, and means 35 for adjusting said last named means to determine the range of movement of the ignition spark device.

9. The combination with throttle and ignition spark devices, of means connecting said 40 devices to secure synchronous movement thereof, and means for breaking said connection when the spark device is at fully advanced position.

10. The combination with throttle and ignition spark devices, of means connecting said devices to secure synchronous movement thereof, means for breaking said connection when the spark device is at fully advanced position, and other means for 45 breaking said connection before the spark device has reached fully advanced position.

11. The combination with throttle and ignition spark devices, of means normally connecting said devices to secure synchronous actuation thereof, mechanical means for actuating one of the devices, means for breaking said connection when the spark device has reached fully advanced position, and adjustable means for breaking said connection before the spark device has reached fully advanced position whereby range of spark advance may be limited without limiting the throttle range.

12. The combination with throttle and ignition spark devices, of means for connect-

ing said devices to secure synchronous movement thereof, and means for limiting movement of the spark device to determine the range of the latter irrespective of the range of the throttle.

13. The combination with ignition and spark devices, of releasable connection between said devices, a fixed stop for breaking said connection when the spark device is at fully advanced position, and an adjustable 75 stop for breaking said connection or limiting movement of the spark device to determine the range of spark advance or retard and permit movement of the throttle beyond the limit of said range.

14. The combination with a throttle valve, of a movable member for actuating said valve, an ignition spark device, a member connected with said spark device and adapted for releasably connecting the same 85 with said movable member, and a stop adapted for engagement by said releasable member to break its connection with the movable member, for the purpose set forth.

15. The combination with a throttle valve, 90 of a movable member for actuating said valve, an ignition spark device, a member connected with said spark device and adapted for releasably connecting the same with said movable member, a stop adapted for engagement by said releasable member to break its connection with the movable member, and means for adjusting said stop.

16. The combination with a throttle and an ignition spark device, of a movable member for actuating the spark device, a releasable member on the spark device for engaging the movable throttle member to induce synchronous movement of the movable members, an adjustable stop device adapted 105 for engagement by the releasable member or by the movable spark device member to break the connection between the movable throttle and the movable spark device member, whereby the range of movement of the 110 spark device is limited, for the purpose set forth.

17. The combination with a throttle and with an ignition spark device, of movable 115 means for actuating the throttle, movable means for actuating the spark device, an arm on the movable spark device adapted for releasably connecting the same with the movable throttle means, and a stop movable in either direction from a neutral point and adapted for engagement by the releasable arm at one side of the neutral point to break connection between said movable members and limit advance of the spark and for engagement by the movable spark member when at the other side of neutral to limit movement of the spark device toward retard position.

18. The combination with a throttle and an ignition spark device, of a reciprocatory 130

rod for actuating the throttle, a reciprocatory yoke connected with the ignition spark device, an arm pivotally mounted on said yoke and adapted to cramp on the throttle rod, and a stop located between said arm and one arm of the yoke and adapted for engagement by either to break the cramp connection of said arm with the throttle rod or to stop movement of the spark device toward retard position.

19. The combination with throttle and spark devices, of a reciprocatory member operatively connected with each device, a yoke fixed on the reciprocatory spark device member, an arm pivotally mounted on said yoke and lying along the reciprocatory throttle member, yielding means for cramping said arm on the reciprocatory throttle member, a fixed stop for engaging said arm 20 to release the throttle member, and an adjustable stop movable in either direction from the fixed stop to engage the pivoted

arm or the fixed arm, for the purpose set forth.

20. The combination with a throttle and 25 an ignition spark device, of a frame comprising spaced arms, a rod slidable in said frame and connected with the throttle, a rod slidable in said frame and connected with the spark device, a yoke fixed on the spark 30 device rod and slidable on the throttle rod, an arm pivotally mounted on said yoke and slidable on the throttle rod, a spring normally cramping the arm on said rod, a fixed stop for engagement by the pivoted arm to 35 break the cramped connection, an adjustable stop movable in either direction from the fixed stop to position for engagement by the yoke arm to limit the range of movement of the spark device with the throttle, substantially as set forth.

In testimony whereof I affix my signature.

GEORGE B. MAEGLY.
